ANDREW R. RIDDERSTROM, OF NAHANT, MASSACHUSETTS, ASSIGNOR TO BEACON FOLDING MACHINE COMPANY, OF LYNN, MASSACHUSETTS, A CORPORATION OF MASSACHUSETTS.

FOLDING MACHINE AND METHOD.

Application filed November 3, 1922. Serial No. 598,716.

The present invention relates more particularly to methods of and machines for folding a binding strip around the edge of a boot or shoe upper to which it is attached.

5 The machine that is illustrated, described and claimed in Patent No. 1,527,396, granted February 24, 1925, is very well adapted to folding binding strips of cloth, silk and the like, and also to folding binding strips made 10 of heavier materials, like leather. Leather binding strips are thicker than cloth, silk and the like, however, so that the finally folded, leather binding strip stands out very markedly upon the boot or shoe upper to 15 which it is attached, along the line of attachment.

It is therefore an object of the present invention to provide an improved method 20 of folding leather binding strips, whereby the folded leather binding strip may be caused to lie substantially flush with the face of the upper to which it is attached, along the line of attachment; and to provide an 25 improved machine for carrying out the method. Other objects will appear herein- after.

The invention will be better understood by referring to the accompanying drawings, in which Fig. 1 is a perspective view of the 30 upper, forward part of a machine constructed as described in the above-identified application, but modified in accordance with the present invention, parts being broken away for clearness; Fig. 2 is a similar fragmentary plan view, illustrating the operation of the machine shown in Fig. 1; Fig. 3 is a 35 similar fragmentary perspective view, illustrating the folding action at a sharp, convex curve; Fig. 4 is a sectional view of a shoe upper, showing a binding strip as it 40 usually appears when attached to an edge of the upper; and Figs. 5 and 6 are sections similar to Fig. 4, illustrating steps in folding the binding strip around the shoe upper.

45 The invention is illustrated in the accompanying drawings in connection with the folding of a binding strip 2, of leather and the like, around the edge 4 of a sheet of leather or other material 6, such as a boot 50 or shoe upper. An edge 8 of the binding strip is sewed to a face 10 of the shoe upper, along the edge 4, so that the sheet and the strip extend at an angle to each other from the secured-together edges 4 and 8. It will

be understood that the invention is equally applicable to other articles than that which is herein chosen for purposes of illustration, and the elements of the article need not necessarily be of the relative dimensions shown.

As in the machine of the above-described patent, the shoe upper is initially placed upon a platform or support 24, with the face 10 of the upper in contact with the support. The free edge 26 of the strip 2 is initially 65 moved across and around the secured-together edges 4 and 8, into the space between an interior side face 28 of a feed point 30 and a plow 32 that stands up integrally from a plate 34 by which it is carried. The 70 machine being set into operation, successive portions of the strip 2 are intermittently wiped tightly across the secured-together edges 4 and 8, by the combined action of a wiper 38 and a retainer point 246 that 75 presses down heavily at this time upon the upper, directly opposite to the point of action of the wiper. The successively wiped portions are initially intermittently folded around the secured-together edges 4 and 8 80 by the plow and they are gripped intermittently between the interior side face 28 of the feed point and the upstanding plow 32, becoming thereby pulled tightly. The 85 intermittent wiping, and folding and gripping operations are performed upon the successive portions of the strip alternately. The folded portions are then advanced by the feed point and a cooperating feed block 41 to a folder 42. This folder, hereinafter for 90 definiteness to be referred to as a fold presser, presses down the initially formed folds into even contact with the face 16 of the sheet, as shown in Figure 6. These operations are continued in timed relation to each 95 other until the whole strip has become folded.

The wiper acts intermittently, at spaced or separated portions only of the strip, in a direction rearwardly oblique to the strip and 100 oblique to the plane of the leather sheet, as described in the above-identified patent. It first engages the strip at substantially the point where the strip is attached to the leather sheet, and moves in the direction of 105 the arrow of Figure 2, forward, and obliquely towards the unsecured edge 26 of the strip. In so doing, it bites firmly into

the strip and wipes it tightly across the secured-together edges 4 and 8. The successive, active wiping portions of the wiper remain at the same level, directly opposite the retainer so that the retainer, when operating idly, can not engage the wiper and injure it. The wiper then returns, and the cycle of operations is repeated, the stock having meanwhile been fed forward another step. To effect the desired operation of the wiper, it is mounted over a crank stem or eccentric 31 that is obliquely or diagonally mounted at the end of a rotating shaft 52. The shaft 52 is rotated by mechanism fully described in the above-mentioned patent. As the shaft 52 is rotated, the obliquely disposed crank stem 31 will be moved so as to cause the wiper to be wiggled in a fashion that will be readily understood by persons skilled in the art. Reference is made to the said patent for further details of construction, and for a description of the manner in which the feed block 41 and the feed point 30 are reciprocated towards and from the fold presser 42. It is sufficient to state here that during the backward movement of the feed elements and the plow from the fold presser towards the wiper, the feed point first rises and then, towards the end of the backward movement, it descends again. During this backward movement, a space is provided between the interior face 28 of the feed point and the plow, allowing the strip 2 in between to become slack or loose. The plow is thus enabled to fold most effectively, without interference from friction by the feed point.

The binding strip is maintained in folded position upon the face 16 of the leather by previously applied cement. If the initially folded strip were permitted to contact with the edges 4 and 8 before it has become tightly gripped and pulled tight by the combined action of the feed point and the plow, it would not be possible to pull the strip tight, and the resulting fold would be defective. A separator 143 is therefore provided just in front of the plow to maintain the strip separated from the raw edges 4 and 8 until after the feed point and the plow have had an opportunity to pull the strip tight. The separator 143 is maintained in place between the binding strip and the raw edges 4 and 8 until the forward movement of the feed elements, carrying the stock with them, causes the separator to be left behind. The binding strip can not, therefore, stick to the edges 4 and 8 before it has been properly folded over.

The upper is advanced by the feed elements and the plow to a diagonally offset edge 144 of the fold presser 42, under which edge the initially plow-folded strip is positioned and by which it is pinched at the very fold. The pinched fold is later pressed into even contact with the face 16 of the upper. The exterior surface of the fold presser is cylindrical, as shown at 156, so as to rock within a cylindrical bearing 158 provided at the free end of an arm 160. The curvilinear working face 164 of the fold presser descends with a rolling action upon the strip. The previously pinched fold, after it is advanced, on the next feed movement, under the cylindrical face 164, is thus pressed out or rolled over. The fold presser is spring-pressed towards the support 24 by a compression spring 166 mounted upon a rod 168 extending through an opening (not shown) in the arm 160 and screw-threaded into the frame. By means of the screw threads, the pressure of the spring upon the arm 160 may be adjusted, the ends of the spring being confined between the arm and a knurled head 170 upon the rod 168. The working face 164 of the fold presser may be provided with teeth or may be otherwise roughened, to enable it to secure a firm grip upon the strip at thickened places, such as seams, thereby overcoming the tendency which the fold presser would otherwise have to push the stock away instead of ironing it out. The feed point is preferably also provided with gripping teeth.

The retainer point 246 is carried by a retainer 153 and presses down upon the stock to prevent the stock being pushed outward away from the operating instrumentalities of the machine; to hold the stock firmly against accidental movement during the return movement of the feed elements; and, co-operating with the wiper, to grip the stock at a point near the raw edge, directly opposed to the point of action of the wiper, and to hold the stock while the wiper performs its wiping action.

An arm 250 of somewhat greater length than that of the retainer point is provided for the purpose of contacting with a stationary part of the machine at 252, so that when the machine runs idly, the retainer point 246 cannot become lowered into contact with the wiper and, by hammering away at the wiper, injure it. The retainer is shown bowed out at 248 so as not to obstruct the view of the operator. The retainer point 246 is provided with teeth (not shown), the more firmly to hold the stock. The retainer presses down firmly, and the wiper wipes, during the return movement of the feed elements. Upon the feed elements resecuring their grip upon the stock, in preparation for another feed movement, the wiper and the retainer release their hold upon the stock, the wiper moving downward, away from the stock as has already been described, and the retainer similarly moving upward.

The foregoing brief description of the machine of the aforementioned patent will suffice as a setting for the features of

novelty that are now to be explained, and it will be understood that the said features of novelty are not restricted to any particular machine, the machine of the said patent being chosen for illustrative purposes only, to make clearer the description that is now to follow.

An object of the present invention is to cause the folded leather or other binding strip 2 to lie substantially flush with the face 10 of the upper 6 at 233, along the line of its attachment to the upper. As shown in Figs. 3 and 6, this is accomplished, according to the preferred embodiment of the present invention, by hollowing out the face 10 of the upper near the line 233, and filling in the hollow with the near-lying portions of the strip 2.

To bring about this result, the sheet 6 is not fed over the support 24 in quite flat condition, as in the said prior patent, but successive portions of the margin of the sheet, along the edge 4, are bent a little out of the plane of the sheet upward, or 25 in a direction away from the stitched portion of the strip 2. In order to avoid circumlocution of language, the expression "bending up the edge of the sheet" or its equivalent will be employed in the specification and the claims to denote such bending of the margin of the sheet in a direction away from the stitched portion of the strip 2. The unsecured portion of the strip is moved lightly across the secured-together edges, as is illustrated in Fig. 5. The sheet is fed forward, with its margin and the binding strip in this successively bent condition, to the operating instrumentalities of the machine, as before described, and as is 30 explained in greater detail in the aforesaid patent. The unsecured portions of the strip adjacent to the successively bent portions are successively wiped by the wiper 38 across the secured-together edges 4 and 8, folded by the plow around these edges, and pressed by the fold presser 42. The fold presser will not, however, act quite in the same way as heretofore described, because it will now press the folded strip not only 35 against the margin of the sheet, but also against the bent-up edge. The pressure exerted by the fold presser will cause the leather of the sheet 6 to conform to the shape determined by its initial position illustrated in Fig. 5, with the ultimate result that the portion of the strip near the line of 40 stitches 233 will become seated in a hollow of the leather sheet, substantially flush with the face 10, as illustrated in Fig. 6. The 45 upstanding bent edge of the sheet shown in Fig. 5 will become compressed substantially flat with the face 10 of the sheet, as is also illustrated in Fig. 6. This compressing action causes the strip 2 to be pulled tightly 50 away from the upper 6 at the stitches 233

within the angle between the sheet and the strip. For this reason, it is found, in practice, that the wiper is really unnecessary,—though it may be used,—since the tight pulling away of the strip 2 at the stitches 233 55 may be effected by the fold presser if the stock is properly presented thereto, as above described.

The above-described bending of the successive portions of the margin of the sheet 6 may be effected in many ways without departing from the spirit or scope of the present invention. The preferred construction, which has been found to be very effective, in practice, consists in simply recessing the feed point 30 at 29, where an unrecessed feed point would engage the margin at the edge 4. The recessed feed point can therefore clamp only those portions of the stock that are adjacent to the edge 4, leaving the portions at the edge 4 unclamped. When the feed point clamps the said portions of the stock, therefore, the strip 2, acting against the feed block 41 and the plow 32, causes the margin at the edge 4 to lift or bend into the recess 29. The feed point and the feed block therefore advance the stock with the margin near the edge 4 bent up into the recess 29, as is illustrated in Fig. 5. The wiper 38 is similarly provided with a recess 39 adapted to receive the portions of the strip 2 adjacent to the secured-together edges, as is also clearly illustrated in Fig. 5. This construction, furthermore, enables the wiper to grip the strip, in its wiping action, very close to the line 233 where it is sewed to the upper, and is a very effective aid to tight wiping. The plow 32 is for a like purpose somewhat further hollowed out at 33.

The invention is obviously not limited to the modifications that are shown embodied herein. Other machines and other modifications are within the skill of persons skilled in the art, and all such are considered to be within the spirit of the invention, the scope of which is defined in the appended claims. It is intended to express in the appended claims all features of novelty that are disclosed herein.

What is claimed is:

1. The method of folding a strip around the edge of a sheet of material to one face of which, along the said edge, an edge of the strip is secured so that the sheet and the strip extend from the secured-together edges at an angle to each other, the said method comprising moving successive portions of the strip across the secured-together edges, folding successive portions of the strip around the secured-together edges, bending up successive portions of the said edge of the sheet, and pressing successive portions of the strip against the other face of the sheet.

2. A machine of the class described having, in combination, a support upon which is adapted to rest a sheet of material to one face of which, along an edge, an edge of a strip is secured so that the sheet and the strip extend from the secured-together edges at an angle to each other, means for moving the unsecured portion of the strip across the secured-together edges, and means for bending up the said edge of the sheet and for feeding the sheet over the support. 70
3. A folding machine for operating upon a piece of work comprising a sheet of material to one face of which, along an edge, a strip is secured, the said machine having, in combination, means for supporting the sheet and the strip, means for folding the strip over upon the sheet, bending up the said edge of the sheet, and feeding the sheet and the strip over the supporting means, and means for operating any part of the second-named means. 78
4. A machine for folding a strip around the edge of a sheet of material to one face of which, along the said edge, an edge of the strip is secured so that the sheet and the strip extend from the secured-together edges at an angle to each other, the said machine having, in combination, means for bending up the said edge of the sheet and for feeding the sheet with the edge so bent and with the free portion of the strip moved across the secured-together edges, a wiper for wiping the free portion of the strip adjacent to the bent portion of the sheet across the secured-together edges, the said means comprising a plow for folding the wiped strip around the secured-together edges, and a fold presser for pressing the folded strip against the bent edge and the margin along the other face of the sheet. 85
5. A machine for folding a strip around the edge of a sheet of material to one face of which, along the said edge, an edge of the strip is secured so that the sheet and the strip extend from the secured-together edges at an angle to each other, the said machine having, in combination, two feed elements for feeding the sheet with the said edge of the sheet bent up, one of the feed elements having a recess adapted to receive the said bent edge of the sheet, and means for folding the free portion of the strip around the bent edge of the sheet. 90
6. In a machine for folding a strip around the edge of a sheet of material to one face of which, along the said edge, an edge of the strip is secured so that the sheet and the strip extend from the secured-together edges at an angle to each other, a support upon which the sheet is adapted to rest with the said edge of the sheet bent up and with the unsecured portion of the strip moved across the secured-together edges, and a wiper for wiping the unsecured por- 95
- tions of the strip adjacent to the secured-together edges across the secured-together edges, the wiper having a recess adapted to receive the said portions of the strip adjacent to the secured-together edges. 100
7. A machine for folding a strip around the edge of a sheet of material to one face of which, along the said edge, an edge of the strip is secured so that the sheet and the strip extend from the secured-together edges at an angle to each other, the said machine having, in combination, a feed block and a feed point for feeding the sheet with the said edge of the sheet bent up and with the unsecured portion of the strip moved across the secured-together edges, the feed point having a recess adapted to receive the said bent edge of the sheet, a wiper for wiping the unsecured portions of the strip adjacent to the secured-together edges across the secured-together edges, the wiper having a recess adapted to receive the said portions of the strip adjacent to the secured-together edges, a plow for folding the strip around the secured-together edges, and a fold presser for pressing the folded portions of the strip against the edge and the margin along the other face of the sheet. 105
8. A machine as defined in claim 4 in which the plow is hollowed out at the base thereof to receive the portions of the strip adjacent to the secured-together edges. 110
9. The method of folding a strip around the edge of a sheet of material to one face of which, along the said edge, an edge of the strip is secured so that the sheet and the strip extend from the secured-together edges at an angle to each other, the said method comprising moving the free portion of the strip across the secured-together edges, folding the moved portion of the strip around the secured-together edges, and bending up the sheet at the said edge of the sheet. 115
10. The method of folding a strip around the edge of a sheet of material to one face of which, along the said edge, an edge of the strip is secured so that the sheet and the strip extend from the secured-together edges at an angle to each other, the said method comprising folding the free portion of the strip around the secured-together edges, bending up the sheet, at the said edge of the sheet, and pressing the folded strip against the bent edge and the margin along the other face of the sheet to compress the upstanding bent edge of the sheet and to press the folded portion of the strip into contact with the said other face of the sheet. 120
11. The method of folding a strip around the edge of a sheet of material to one face of which, along the said edge, an edge of the strip is stitched, so that the sheet and the strip extend from the stitched-together edges at an angle to each other, the said method comprising folding the free por- 125
- 150

- tions of the strip successively around the stitched-together edges, feeding the sheet and the strip, bending up successive portions of the sheet, at the said edge of the sheet, under the folded portions of the strip, and applying pressure to the successively folded portions of the strip and, through them, to the bent-up edge portions of the sheet to pull the successive portions of the sheet to pull the successive portions of the strip away from the sheet at the stitch line and to compress the successively bent-up portions of the edge of the sheet and to press the successively folded portions of the strip into contact with the said other face of the sheet.
12. The method of folding a strip around the edge of a sheet of material to one face of which, along the said edge, an edge of the strip is stitched so that the sheet and the strip extend from the stitched-together edges at an angle to each other, the said method comprising folding the free portion of the strip around the stitched-together edges, bending up the sheet at the said edge of the sheet, under the folded portion of the strip, applying pressure to the folded portion of the strip and, through it, to the bent-up edge portion of the sheet to pull the strip away from the sheet at the stitch line and to compress the said bent-up edge of the sheet, and rolling the strip against the margin adjacent to the said bent-up edge along the said other face of the sheet to press the folded portion of the strip into contact with the said other face of the sheet.
13. The method of folding a strip around the edge of a sheet of material to one face of which, along the said edge, an edge of the strip is stitched so that the sheet and the strip extend from the stitched-together edges at an angle to each other, the said method comprising feeding the sheet and the strip, folding the free portions of the strip successively around the stitched-together edges, bending up successive portions of the sheet, at the said edge of the sheet, under the folded portions of the strip, applying pressure to the successively folded portions of the strip and, through them, to the bent-up edge portions of the sheet to pull the successive portions of the strip away from the sheet at the stitch line and to compress the successively bent-up portions of the edge of the sheet, and rolling the successively folded portions of the strip against the portions of the margin adjacent to the said bent-up edge along the said other face of the sheet to press the folded portions of the strip into contact with the said other face of the sheet.
14. The method of folding a strip around the edge of a sheet of material to one face of which, along the said edge, an edge of the strip is stitched so that the sheet and the strip extend from the stitched-together edges at an angle to each other, the said method comprising folding the free portions of the strip around the stitched-together edges, bending up successive portions of the sheet, at the said edge of the sheet, under the folded portions of the strip, holding the sheet on both sides of the sheet adjacent to the successively folded portions of the strip, pinching the successively folded portions of the strip at the folds adjacent to the successively held portions of the sheet and, through them, pinching the adjacent bent-up portions of the edge of the sheet along the other face of the sheet to pull the successive portions of the strip away from the sheet at the stitch line and to compress the successively bent-up portions of the edge of the sheet, and pressing the successively folded portions of the strip into contact with the said other face of the sheet.
15. A machine for folding a strip around the edge of a sheet of material to one face of which, along the said edge, an edge of the strip is secured so that the sheet and the strip extend from the secured-together edges at an angle to each other, the said machine having, in combination, means for moving the free portion of the strip across the secured-together edges, and means for folding the free portion of the strip around the secured-together edges, bending up the sheet at the said edge of the sheet and pressing the folded portion of the strip against the edge and the margin along the other face of the sheet to compress the bent-up edge of the sheet and to press the folded portion of the strip into contact with the said other face of the sheet.
16. A machine for folding a strip around the edge of a sheet of material to one face of which, along the said edge, an edge of the strip is stitched so that the sheet and the strip extend from the stitched-together edges at an angle to each other, the said machine having, in combination, means for folding the free portions of the strip successively around the stitched-together edges, bending up successive portions of the sheet, at the said edge of the sheet, under the folded portions of the strip, and feeding the sheet with the edge so bent, and means for applying pressure to the successively folded portions of the strip and, through them, to the bent-up edge portions of the sheet to pull the successive portions of the strip away from the sheet at the stitch line, to compress the successively bent-up portions of the edge of the sheet and to press the successively folded portions of the strip into contact with the said other face of the sheet.
17. A machine for folding a strip around the edge of a sheet of material to one face of which, along the said edge, an edge of the

- strip is stitched so that the sheet and the strip extend from the stitched-together edges at an angle to each other, the said machine having, in combination, means for supporting the sheet and the strip, means for folding the free portions of the strip successively around the stitched-together edges, bending up successive portions of the sheet, at the said edge of the sheet, under the folded portions of the strip, applying pressure to the successively folded portions of the strip and, through them, to the bent-up edge portions of the sheet to pull the successive portions of the strip away from the sheet at the stitch line and to compress the successively bent-up portions of the edge of the sheet, and rolling the successively folded portions of the strip against the adjacent portions of the margin along the said other face of the sheet to press the folded portions of the strip into contact with the said other face of the sheet, and means for operating any part of the second-named means, the supporting means and the material being constructed and arranged for relative movement to bring successive portions of the material into operative relation to the operating means. 18. A machine for folding a strip around the edge of a sheet of material to one face of which, along the said edge, an edge of the strip is stitched so that the sheet and the strip extend from the stitched-together edges at an angle to each other, the said machine having, in combination, means for supporting the sheet and the strip, means for folding the free portions of the strip successively around the stitched-together edges, feeding the sheet with successive portions of the sheet, at the said edge of the sheet, bent up under the folded portions of the strip, applying pressure to the successively folded portions of the strip and, through them, to the bent-up edge portions of the sheet to pull the successive portions of the strip away from the sheet at the stitch line and to compress the successively bent-up portions of the edge of the sheet, and rolling the successively folded portions of the strip against the adjacent portions of the margin along the said other face of the sheet to press the folded portions of the strip into contact with the said other face of the sheet, and means for operating any part of the second-named means. 19. A folding machine for operating upon a piece of work comprising a sheet of material to one face of which, along an edge, a strip is secured, the said machine having, in combination, means for supporting the sheet and the strip, means for folding the strip over upon the sheet, bending up the sheet, at the said edge, and pressing the folded strip against the other face of the sheet, and means for operating any part of the second-named means. 20. A folding machine for operating upon a piece of work comprising a sheet of material to one face of which, along an edge, a strip is secured, the said machine having, in combination, means for supporting the sheet and the strip, means for folding successive portions of the strip successively over upon the sheet, bending up successive portions of the sheet, at the said edge, and pressing the successively folded portions of the strip against the successive portions of the bent edge and adjacent portions of the margin of the sheet along the other face of the sheet, and means for operating any part of the second-named means, the supporting means and the material being constructed and arranged for relative movement to bring successive portions of the material into operative relation to the operating means. 21. A folding machine for operating upon a piece of work comprising a sheet of material to one face of which, along an edge, a strip is secured, the said machine having, in combination, means for feeding the sheet and the strip and for folding the strip around the said edge, the said means having elements for bending up successive portions of the margin of the sheet, at the said edge, one of the elements being constituted of a folder adapted to fold portions of the strip successively around the said edge, and a fold presser for pressing the successively folded portions of the strip against the said portions of the bent margin and the adjacent portions of the margin along the other face of the sheet. 22. A machine for folding a strip around the edge of a sheet of material to one face of which, along the said edge, an edge of the strip is stitched so that the sheet and the strip extend from the stitched-together edges at an angle to each other, the said machine having, in combination, means for successively engaging successive portions of the sheet on both sides of the sheet, and means for folding the free portions of the strip adjacent to the successively engaged portions of the sheet successively around the stitched-together edges, bending up successive portions of the sheet, at the said edge of the sheet, under the folded portions of the strip, applying pressure to the successively folded portions of the strip adjacent to the successively engaged portions of the sheet and, through them, to the bent-up edge portions of the sheet to pull the successive portions of the strip away from the sheet at the stitch line and to compress the successively bent-up edge portions of the sheet, and pressing the successively folded portions of the strip into contact with the said other face of the sheet. 23. A folding machine for operating upon a piece of work comprising a sheet of material to one face of which, along an edge, a strip is secured, the said machine having, in combination, means for supporting the sheet and the strip, means for folding the strip over upon the sheet, bending up the sheet, at the said edge, and pressing the folded strip against the other face of the sheet.

23. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet with successive portions of the margin of the sheet, at the said edge, bent 10 out of the plane of the sheet in a direction away from the strip, and a combined gage and plow for gaging the sheet and folding the strip.
24. The method of folding a strip around the edge of a sheet of material to one face of which, along the said edge, an edge of the strip is secured so that the sheet and the strip extend from the secured-together edges at an angle to each other, the said method 15 comprising folding the free portions of the strip successively around the secured-together edges, bending up successive portions of the margin of the sheet, at the said edge of the sheet, and pressing the successively 20 folded portions of the strip into contact with the other face of the sheet.
25. A folding machine for operating upon a piece of work comprising a sheet of material to one face of which, along an edge, 25 a strip is secured, the said machine having, in combination, means for folding the strip over upon the sheet and bending up the sheet at the said edge, and means for pressing the strip into contact with the other face of the sheet.
26. The method of folding a strip around the edge of a sheet of material to one face of which, along the said edge, an edge of the strip is secured so that the sheet and the strip extend from the secured-together edges at an angle to each other, the said method 30 comprising folding the free portions of the strip successively around the secured-together edges, gripping successive portions of the sheet adjacent to the said edge of the sheet, feeding the sheet and the strip, bending up the portions of the sheet adjacent to the said successive gripped portions, and pressing the successively folded portions of the strip against the edge and the margin 35 along the other face of the sheet.
27. A folding machine for operating upon a piece of work comprising a sheet of material to one face of which, along an edge, a strip is secured, the said machine having, in combination, means for supporting the sheet and the strip, means for successively engaging, at the other face of the sheet, successive 40 portions of the sheet, and means for folding the free portions of the strip adjacent to the successively engaged portions of the sheet over upon the sheet, bending up successive portions of the sheet at the said edge of the sheet, and pressing the successively folded 45 portions of the strip against the said edge and margin along the said other face of the sheet close to the engaged portions of the sheet, the supporting means and the material being constructed and arranged for relative movement to bring successive portions of the material into operation relative to the operating means.
28. A machine for folding a strip around the edge of a sheet of material to one face of which, along the said edge, an edge of the strip is secured so that the sheet and the strip extend from the secured-together edges at an angle to each other, the said machine having, in combination, means for bending the margin of the sheet, at the said edge, out 50 of the plane of the sheet in a direction away from the strip and for feeding the sheet and the strip with the margin so bent and with the unsecured portion of the strip moved across the secured-together edges, the said means comprising a plow for folding the strip around the secured-together edges, and a fold presser for pressing the folded sheet against the bent edge and the margin along the other face of the sheet.
29. A folding machine for operating upon a piece of work comprising a sheet of material to one face of which, along an edge, a strip is secured, there being a ridge at the junction between the sheet and the strip, the said machine having, in combination, a member for engaging the strip having a recess adapted to receive the ridge, and means for feeding the sheet and the strip and pressing the strip into contact with the other face of the sheet.
30. A folding machine for operating upon a piece of work comprising a sheet of material to one face of which, along an edge, a strip is secured, there being a ridge at the junction between the sheet and the strip, the said machine having, in combination, a member for engaging the strip having a recess adapted to receive the ridge, and means for bending up the sheet at the said edge and folding the strip over upon the sheet.
31. The method of folding a strip around the edge of a sheet of material to one face of which, along the said edge, an edge of the strip is secured so that the sheet and the strip extend from the secured-together edges at an angle to each other, the said method comprising folding the strip around the secured-together edges, bending up the sheet at the said edge of the sheet, and feeding the sheet and the strip with the said edge of the sheet so bent.
32. The method of folding a strip around the edge of a sheet of material to one face of which, along the said edge, an edge of the strip is stitched so that the sheet and the strip extend from the stitched-together edges at an angle to each other, the said method comprising folding the free portion of the strip around the stitched-together edges, bending

up the sheet at the said edge of the sheet under the folded portions of the strip, and applying pressure to the folded strip and, through it, to the bent-up edge of the sheet 5 to pull the strip away from the sheet at the stitch line and to compress the bent-up edge of the sheet.

33. The method of folding a strip around the edge of a sheet of material to one face 10 of which, along the said edge, an edge of the strip is secured so that the sheet and the strip extend from the secured-together edges at an angle to each other, the said method comprising folding the strip around 15 the secured-together edges, bending up the sheet at the said edge of the sheet, feeding the sheet and the strip with the said edge of the sheet so bent, and pressing the strip against the other face of the sheet.

34. The method of folding a strip around the edge of a sheet of material to one face of which, along the said edge, an edge of the strip is stitched so that the sheet and the strip extend from the stitched-together 20 edges at an angle to each other, the said method comprising folding the free portion of the strip around the stitched-together edges, bending up the sheet at the said edge of the sheet under the folded portions of the strip, feeding the sheet and the strip, and applying pressure to successive portions of the folded strip and, through them, to the successive portions of the bent-up edge of the sheet to pull the strip away from the 25 sheet at the stitch line and to compress the bent-up edge of the sheet.

35. A folding machine for operating upon a piece of work comprising a sheet of material to one face of which, along an edge, 30 the strip is secured, the said machine having, in combination, a plurality of elements for feeding the sheet and the strip, bending up the sheet at the said edge, and folding the strip over upon the sheet, one of the elements 35 constituting the means for folding the strip around the said edge.

36. A folding machine for operating upon a piece of work comprising a sheet of material to one face of which, along an edge, 40 a strip is secured, the said machine having, in combination, means for bending up the sheet, at the said edge, feeding the sheet and the strip, and folding the strip over upon the sheet, and means for pressing the strip against the other face of the sheet. 45

37. A folding machine for operating upon a piece of work comprising a sheet of material to one face of which, along an edge, 50 a strip is secured, the said machine having, in combination, two relatively movable members for gripping the sheet and the strip adjacent to the said edge, one of the members having a portion adapted to engage 55 the margin of the sheet near the said edge to

bend up the said edge and the other member being shaped to permit the said edge to be bent up when the sheet and the strip are gripped between the two members, and means for folding the strip over upon the sheet. 60

38. A folding machine for operating upon a piece of work comprising a sheet of material to one face of which, along an edge, 65 a strip is secured, the said machine having, in combination, means for folding the strip over upon the sheet, bending up the sheet at the said edge, and feeding the sheet and the strip, the said means having a recess or cut-away portion for receiving the bent-up edge, and means for operating any part of the said means. 70

39. A folding machine for operating upon a piece of work comprising a sheet of material to one face of which, along an edge, 75 a strip is secured, the said machine having, in combination, a plurality of elements for feeding the sheet and the strip, bending up the sheet at the said edge, folding the strip over upon the sheet, and pressing the strip against the other face of the sheet, two of the said elements constituting the feeding means, one of the said two elements having a recess or cut-away portion for receiving 80 the bent-up edge. 85

40. A folding machine for operating upon a piece of work comprising a sheet of material to one face of which, along an edge, 90 a strip is secured, the said machine having, in combination, means for folding the strip over upon the sheet, and means for feeding the sheet and the strip and for pressing the strip against the other face of the sheet, the two said means cooperating to bend up the edge of the sheet. 95

41. A machine for folding a strip around the edge of a sheet of material to one face of which, along the said edge, an edge of the strip is stitched so that the sheet and the strip extend from the stitched-together 100 edges at an angle to each other, the said machine having, in combination, means for supporting the sheet and the strip, means for folding the free portion of the strip around the stitched-together edges, bending up the sheet, at the said edge of the sheet, under the folded portions of the strip, feeding the sheet and the strip over the supporting means, and applying pressure to the folded 105 portions of the strip and, through them, to the bent-up edge portions of the sheet to

pull the strip away from the sheet at the stitch line and to compress the bent-up edge portions of the sheet, and means for operating any part of the second-named means. 110

42. A folding machine for operating upon a piece of work comprising a sheet of material to one face of which, along an edge, 115 a strip is secured, there being a ridge at the junction between the sheet and the strip, the 120

said machine having, in combination, a plurality of elements for bending up the sheet at the said edge, and pressing the strip against the other face of the sheet, one of the elements having a hollowed-out portion adapted to receive the ridge.

43. A folding machine for operating upon a piece of work comprising a sheet of material to one face of which, along an edge, a strip is secured, there being a ridge at the junction between the sheet and the strip, the said machine having, in combination, a plurality of elements for bending up the sheet at the said edge, feeding the sheet and the strip and pressing the strip against the other face of the sheet, one of the elements having a hollowed-out portion adapted to receive the ridge.

44. A folding machine for operating upon a piece of work comprising a sheet of material to one face of which, along an edge, a strip is secured, there being a ridge at the junction between the sheet and the strip, the said machine having, in combination, a member for engaging the strip having a recess adapted to receive the ridge, and means for bending up the sheet, at the said edge, out of the plane of the sheet in a direction away from the strip, feeding the sheet and the strip and pressing the strip against the other face of the sheet.

In testimony whereof, I have hereunto subscribed my name this 1st day of November, 1922.

ANDREW R. RIDDERSTROM.
